DRINKING CUP

Roland E. Johnson, Cincinnati, Ohio, assignor to Columbus Plastics Products, Inc., Columbus, Ohio, a corporation of Ohio

Filed Oct. 7, 1965, Ser. No. 87,364

Term of patent 14 years

(Cl. D44—9)

FIG. 1 is a perspective view of a drinking cup showing my new design;

FIG. 2 is a side elevational view;

FIG. 3 is a top plan view;

FIG. 4 is a bottom plan view; and

FIG. 5 is an enlarged, fragmentary horizontal sectional view taken along the line 5—5 of FIG. 2.

I claim:

The ornamental design for a drinking cup, substantially as shown.
